UNITED STATES PATENT OFFICE.

MOSES SPENCER, OF SAYLESVILLE, RHODE ISLAND.

PROTECTOR-GUARD FOR TENSION-PULLEYS OF TEXTILE-MACHINES.

1,131,167.

Specification of Letters Patent.

Patented Mar. 9, 1915.

Application filed June 1, 1914. Serial No. 841,972.

To all whom it may concern:

Be it known that I, MOSES SPENCER, a citizen of the United States, residing at Saylesville, in the county of Providence and State of Rhode Island, have invented certain new and useful Improvements in Protector-Guards for Tension-Pulleys of Textile-Machines, of which the following is a specification.

10 This invention relates to means for excluding lint and fibrous matter from the shaft or axle and bearings of rapidly revoluble exposed take-up tension pulleys employed in connection with textile spinning, 15 twisting, winding and spooling machines, and it consists essentially in providing pulleys of the type referred to with relatively stationary oppositely disposed outer side guard-plates or disks positioned contiguous 20 to and inclosing portions of the pulley, substantially as hereinafter set forth and claimed.

In automatic textile spinning machines, as usually constructed, the spindles thereof 25 are revolubly mounted in a pair of laterally separated horizontal bolster-rails, the spindles being positioned parallel with one another at substantially right angles to the plane of the bolster-rails, and having the 30 spindles arranged in a series of independently controlled groups, each group comprising a plurality of the spindles; a main driving-drum being revolubly mounted intermediate of and parallel with the bolster-rails. 35 The spindles of each group are rotated by means of an endless, flexible band or tape passing around the peripheries of the driving-drum, tension-pulley and the spindle-whirls; the tension-pulley being revolubly 40 supported in the lower end of a pivoted, swinging yoke or frame. A serious objection to the use of such former unprotected tension-pulleys is that matter such, for example, as loose pieces of yarn, roving "loose 45 ends," "strings" and lint or fly are liable to, and in fact do catch on the traveling band and are carried along by it, and as the edges of the band pass the contiguous inner surfaces of the yoke or frame supporting the 50 tension-pulley more or less of said loose pieces are thereby brushed or wiped off and gradually accumulate and become wedged

or clogged between the hubs and sides of the pulley and the adjacent surfaces of the bearings and yoke. The presence of such 55 accumulated matter acts to impede the action of the band in that it is caused to slip, thus slackening the normal speed of the corresponding spindles and producing uneven 60 yarn or thread having what is termed a "slack twist." In fact, more particularly in worsted spinning and twisting machines, such fibrous or foreign matter is often drawn onto the revolving pulley and packed into 65 its bearings so tightly as to actually stop the movement of the pulley. By means of my improvement the normal tendency of the device is to prevent the accumulation of said particles of matter, thereby not only 70 overcoming the objections or disadvantages inherent in tension pulleys of this type as formerly employed, but at the same time decreasing the power or working friction, while the degree of twist and tension imparted to the yarn is practically uniform 75 throughout the loaded cop or bobbin.

In the accompanying sheet of drawings, showing an embodiment of my invention coöperating with a tension-pulley and contiguous portions of a textile spinning and twisting machine, Figure 1 represents a side elevation of the pulley, provided with a dust guard and suspended from a swinging frame or hanger in which the pulley is revolubly mounted; Fig. 2 is an edge elevation, 80 portions being omitted; Fig. 3 is a vertical central section, taken on line 3 3 of Fig. 1; Fig. 4 is a partial side elevation, in reduced scale, showing a modification; and Fig. 5 is an enlarged vertical central section, taken on line 5 5 of Fig. 4, the supporting frame or hanger being omitted. 85

The following is a more detailed description of my invention, the same consisting essentially of a tension pulley for textile spinning and twisting machines provided with the mounted dust-guards. 90

The tension-pulley itself, A, has a rim α^2 , preferably provided with a slightly crowned face, a central web α , materially thinner or 100 narrower than said rim, and a central hub α^1 in which is secured a pin or axle d having its end portions projecting through the hub α^1 to form journals or trunnions.

The dust-guards B are each circular or disk-like and having any suitable form, as concavo-convex, cross-sectionally; the center portion being provided with a hub b 5 counterbored from its inner face to snugly receive an anti-friction bushing member b^1 in which the axle d revolves. The extreme outer diameter of the disk B, as represented, is somewhat less than the diameter of the 10 pulley- rim , while the distance, transversely, between the peripheral edges e of the pair of positioned disks B is or may be materially less than the width of the rim, as clearly indicated in Fig. 3. The respective 15 edges e and the corresponding part of the pulley form a narrow peripheral opening p between them when the respective faces of the parts a^1 and b^1 are normally positioned, *i. e.* slightly separated.

20 The supporting arm or hanger C consists of front and back cheeks C^1 C^2 separable on the median line c^1 ; a bolt c^2 serving to accurately position and clamp the cheeks of the arm together. The latter may be integral with the respective dust-guards or 25 disks B as indicated.

The hanger proper is usually suspended from a weighted lever or arm, as m , axially movable on a stationary rod or bar n , the 30 lever having a downward extension m^1 to which the hanger is secured. I make no claim herewith to the hanger nor to means for mounting the same.

In the practical operation of the foregoing elements the mounted tension-pulleys, etc., are capable of being adjusted and actuated to produce in the yarn right or left twist as desired; the improved protecting device operates equally well irrespective of 40 the direction of rotation of the pulley. The normal relation of the guard disks to the revoluble tension-pulley is such that a peripheral opening p is formed between the outer edge of the guard and the contiguous 45 portion of the pulley, and through this opening the pulley freely revolves.

It may be added that bodily movable revoluble tension-pulleys of the general type illustrated herein are employed to automatically 50 compensate or take up the stretch of the traveling bands or tapes driving the respective groups of spindles. The tension-pulley, therefore, is not a driving pulley, but an idler or carrier pulley mounted to 55 revolve on its axle fixed in the hanger, or the pulley may be secured to the mounted axle and revolve with it, the axle in such case being driven by means of the belt and tension-pulley; in either arrangement the 60 pulley A is simply a carrier of the belt and not a driver.

In the modification illustrated in Figs. 4 and 5, the pulley-carrying axle d is revolubly mounted in bushings b^1 secured in 65 normally stationary bearing members b^4 to

which in turn are respectively fixed the protecting disks B. The pulley A, axle d , disks B and bearings b^4 may be bodily removed from the supporting yoke h by first simply swinging the cap plates h^1 on the pivot pins h^3 so as to uncover the bearings b^4 . 70

In my invention the guard-disks may be integral with or fixed to the bearing members so that the latter, including the disks, together with the tension-pulley, are capable 75 of being readily removed bodily from the frame or yoke without segregation, and as readily replaced assembled in the frame.

I claim as my invention and desire to secure by U. S. Letters Patent:— 80

1. A guard-device for tension-pulley mounts for textile spinning and twisting machines comprising the combination with a weighted, pivotally supported swinging hanger member provided with a pair of laterally separated arms having bearings in the free ends thereof, and a revoluble tension-pulley having a short axle mounted in said bearings, of a pair of metal guard disks disposed parallel with and adjacent to the 85 respective lateral sides of the tension-pulley so as to prevent the accumulation in the bearings of loose fibrous matter, and having said guard disks arranged to swing or oscillate bodily with said hanger and pulley 90 members.

2. In a device of the general character described adapted for use in textile spinning and twisting machines, the combination of a tension-pulley mount arranged for swinging movements in a circular arc, said mount having a frame member integral therewith, a tension-pulley, means connected with said frame member for revolvably supporting said pulley therein, and a non-revolvble guard 100 disk positioned contiguous to a side of the pulley, said guard member being secured to and encircling said pulley supporting means, substantially as described.

3. In mounts for tension-pulleys for use 110 in spinning and twisting machines, arranged to automatically take up the slack of traveling endless bands rotating the tension-pulleys, a swinging frame member provided with horizontally disposed alining recesses, 115 bearing members removably positioned in the said recesses, a tension-pulley having its axle supported in the bearing members, caps closing the outer ends of the bearings, and a pair of oppositely arranged disk-like guard 120 members located contiguous to the respective sides of the tension-pulley, said guard members being secured to and extending radially from the said bearing members.

4. In a device of the character described, 125 the combination of a frame member mounted for movement, a pair of spaced apart inwardly facing bearing members alining with each other longitudinally removably secured in the frame member, a tension-pulley dis- 130

posed between the bearing members and revolubly journaled therein, and a pair of protector or guard-disks fixed to the said bearings respectively, said guard-disks being positioned adjacent to the outer lateral sides of the tension-pulley, constructed and arranged so that the assembled said pulley, bearing and guard members are capable of

removal bodily from the frame member without segregation.

In testimony whereof I have affixed my signature in presence of two witnesses.

MOSES SPENCER.
